REINFORCED MONOLITH BUILDING
CONSTRUCTION

Clarence S. Harper, San Diego, Calif.

Application September 20, 1933, Serial No. 690,219

4 Claims.

(Cl. 72—1)

My invention relates to reenforced monolith building construction, and the objects of my invention are:

First, to provide a particularly simple and economically arranged building construction which is inherently fire-proof;

Second, to provide a building construction in which the various frame members or structural members are utilized as molds or forms into which and around which plastic material is applied, thereby eliminating the need of forms or the like, and insuring adequate reenforcing in all parts of the structure;

Third, to provide a building construction in which the various structural members or frame members may be readily and quickly assembled, and varied in their relation to meet the designs of the architect and incorporating means whereby the various structural members may be temporarily attached to each other so that a considerable portion of the frame work may be positioned before applying plastic materials;

Fourth, to provide a building construction wherein various structural members are particularly well interlocked with the concrete or other plastic materials so that the quantity of plastic material will be reduced to a minimum, the structural members carrying a considerable portion of the load;

Fifth, to provide a building construction which is particularly suited for construction with the aid of pneumatic or otherwise supplied plastic material adapted to be delivered through a hose or other flexible conduit;

Sixth, to provide a building construction wherein the various structural members are provided with partially punched out tying elements around and between which the plastic material is poured so as to rigidly anchor the reenforcing relative to the plastic material, the holes from which said punched out portions are formed being so disposed that the various structural members may be temporarily connected by pins, dowels, or other suitable means inserted through aligned holes or apertures;

Seventh, to provide a building construction wherein the holes or other apertures formed in the various structural members permit the partial escape of the cementitious or plastic material so as to form nodules or protruding portions over which plaster may be applied to form an adequate bond therewith; and

Eighth, to provide on the whole a novelly designed building construction, and method of constructing buildings which is durable and provides

a finished structure which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application, in which:

Figure 1 is a fragmentary sectional view of a building wall and the floor and ceiling joist members before the plastic material is applied; Fig. 2 is a fragmentary sectional view of a joist member, floor and inner partition; Fig. 3 is a fragmentary plan view of the base member used to locate and support inner partitions; Fig. 4 is a partial sectional partial elevational view taken substantially along the line 4—4 of Fig. 1; Fig. 5 is a fragmentary sectional view through 5—5 of Fig. 4; Fig. 6 is a fragmentary perspective view of one of the joist members showing the manner in which the floor reenforcing is supported and secured thereto; Fig. 7 is an enlarged transverse sectional view of a completed wall with the plaster applied; Fig. 8 is a similar view of a partially completed wall showing the manner in which the studding may be strengthened; Fig. 9 is a fragmentary sectional view illustrating the manner in which the studding forming member may be adapted to permit connection of such members at right angles to each other; Fig. 10 is a fragmentary sectional view thereof through 10—10 of Fig. 9; and Fig. 11 is a sectional view of the ceiling joist and rafter taken through 11—11 of Fig. 1.

Similar characters of reference refer to similar parts and portions throughout the several views of the drawings.

Foundation 1, studding 2, pins 3, floor joist 4, floor reenforcing 5, floor slab 6, wall reenforcing 7, wall slab 8, reenforcing bars 9, top channel 10, rafters 11, and base channels 12 constitute the principal parts of my reenforced monolith building construction.

A foundation 1 is provided. This is formed from concrete and may be conventional except that there is provided a trench or channel 1a centered along its upper edge. Studding 2 is set at the desired distance and in upright position with its lower ends fitting into the trench or channel 1a.

Each studding member 2 comprises a pair of channel members which are secured together

along their central or base portions 2a. The legs of each channel member are arranged at obtuse angles with the base 2 so that the pairs of legs, designated 2b, formed along each margin of the 5 studding, diverge from the bases or central portions 2a; thereby forming a structural member of substantially X-shaped cross-section. The legs or webs 2b are provided with a series of apertures 2c arranged in columns therealong and 10 preferably in staggered relation. The apertures 2c are formed by partially punching the material inwardly; that is, into the triangular spaces of which the diverging webs form two sides. The apertures 2c are so formed that the tie lugs or 15 elements are larger at their extremities than at their attached ends. The several tying lugs extend substantially horizontally.

The studding is formed of sheet metal so that 20 the tying lugs may be readily stamped therefrom, and the lugs may be variously bent or broken off whenever desired in order that the studding may be connected to other structural members of other similar design. However in most instances 25 the lugs may remain intact. It is quite easy, providing that the apertures 2c are arranged in sufficient frequent intervals, to connect the studding at right angles to each other; thus using the studding for other purposes; for example, it may be desirable to connect several studding intermediate their ends to define to the upper and 30 lower sides of a window or the top of a door frame. This is done by beveling the webs of the member which is to be positioned horizontally, as indicated in Figs. 9 and 10. The beveled end 35 is then positioned against the side of the studding, and a nail or other securing pin 3 is inserted through any apertures that may be in alignment or partially in alignment; thereby providing ample temporary connections between the studding and frame members. It will be noted that 40 this feature of the studding is enhanced by increasing the diverging relation of the webs 2b.

Following out the same principle as embodied 45 in the studding or other frame members similarly formed, joist and other structural members of different section may be provided. The joist members, designated 4, are in the form of relatively deep channels and constructed of sheet metal. The bottom designated 4a is closed and 50 preferably without apertures. The side walls, designated 4b, are provided with a number of horizontal rows of apertures 4c, the apertures in the several rows being arranged in staggered relation. The spacing of the apertures 4c and 55 the transverse spacing of the apertures 2c are so arranged that when a floor joist 4 is placed against the side of a studding member 2, a number of the apertures register so as to receive suitable pins 3, as shown in Figs. 1 and 4.

60 The upper edges of the side walls 4b are provided with a series of short downwardly extending slits, the material between alternate slits being bent horizontally and outwardly forming rudimentary shelves or brackets 4e. The remaining projection, designated 4f remains vertical, as 65 shown best in Fig. 6. The brackets 4e and the upwardly projecting portions 4f serve to connect floor reenforcing 5 thereto. The floor reenforcing 5 is preferably formed of relatively stiff and, 70 if desired, heavy wire. A special type of re-enforcing has been found most suitable. This type comprises wire of relatively large mesh with the strands at right angles to each other, and secured together by spot welding or solder as 75 distinguished from the usual woven wire mesh.

Thus the wire mesh comprises strands 5a which parallel the joist, and other strands 5b which traverse the joist at right angles. Supported from the under side of the strands 5a and 5b is a backing 5c preferably formed of paper and which carries at intervals a tie wire 5d having loop portions 5e at intervals which pass over the strands 5b or 5a so as to support the backing 5c in spaced relation to the wire mesh. In laying the floor reenforcing the paper backing is cut 10 away above each floor joist so as to expose the upper end thereof, and the margins of the paper are rested upon the brackets 4e, as shown best in Fig. 6. The wire mesh is preferably positioned so that the adjacent strands 5a extend 15 along opposite sides of the channel member in contiguous relation therewith; that is, the adjacent strands lie contiguous to the outer sides of the projections 4f so that these projections may be bent into diverging relations, and thereby secure 20 the floor reenforcing in position.

After the joist members are arranged and the floor reenforcing has been positioned thereover, a floor slab of concrete, designated 6, is applied over the reenforcing, and caused to enter the 25 several floor joists 4. The concrete, cement, or plaster is applied in a fairly dry state, but sufficiently wet to fill solidly in the floor joist and ooze or partially protrude from the apertures 4c. The projecting portions or nodules 6a provide 30 excellent means for tying plaster or the like which may be applied over the outside of the floor joist, thereby completely covering the floor joist.

The walls between the studding 2 are covered 35 with wall reenforcing 7 similar to the floor re-enforcing 5. The extremities of the webs 2b may be formed similar to the upper end of the floor joist 4, or may be without the brackets and projecting portions in as much as the strands 40 of the wall reenforcing may be tied by loops of wire through various apertures 2c. After the wall reenforcing 7 is positioned, a wall slab 8 of concrete is applied over the wall with portions 45 of the concrete being poured into the triangular spaces defined by the webs 2b. When the reenforcing 7 and the wall slab have been applied, the studding and walls have the section as illustrated in Fig. 7. If it is desired to further strengthen the walls, particularly if the 50 construction is carried beyond the first story, reenforcing rods 9 may be positioned along and in spaced relation to the bases 2a formed by the members of the studding, and stucco or the like may be applied in the manner of plaster 55 over the surfaces, as shown in Fig. 8. The plaster being forced through the apertures so as to firmly tie itself to the studding; thereupon the wall reenforcing and the wall slab may be applied as above described.

60 The upper end of each studding is provided with a slit 2e extending inwardly from the end and centrally located. The several studding forming a wall support a top channel 10. The top channel 10 is formed similarly to the floor 65 joist 4 except that its base portion 10a is wider, and its side walls 10b are less in height. The side walls 10b are provided with a plurality of apertures 10c formed by pressing portions of the metal inwardly to form tying lugs 10d. 70 In addition to the apertures 10c and the tying lugs 10d, the bottom of the top channel 10 is provided along its side margins with apertures 10e, the material being bent downwardly so as to protrude from the channel and overhang the 75

upper extremities of the studding. The wall reenforcing 7 and wall slab 8 are continued over the side walls 10b of the top channel. The top channel 10 is provided along the center of its base portion 10a with a depending rib 10g which is provided with a series of apertures 10h therein. The apertures 10h are adapted to align with the openings 2c at the upper end of the studding so as to receive a pin or the like 3.

10 If the structure is to be only one story in height, the ceiling joist is rested on top of the top channel 10; however, if the structure is to continue up more than one story, the studding 2 of the second story is supported in the top channel 10 similar to the manner in which the first story studding is mounted in the channel 1a formed in the foundation 1. It should be here noted that the channel 1a after the studding 2 has been positioned, is filled with concrete so as to imbed the lower ends of the studding and hold them in an upright position.

The lower ends of the studding used in the second story are not indicated by 2f at their lower ends, and the apertures 2c align with the apertures 10c so as to receive pins 3 and thereby support the second story studding in a vertical position. The second story floor joist 4 is placed across the top of the channel 10 adjacent the sides of the second story studding, and are tied thereto by means of pins 3 as described hereinbefore. If desired, reenforcing bars 9 may be extended along the top channel. The notches 2f straddle the reenforcing bars 9, as shown best in Figs. 1 and 4.

35 In a similar manner the upper ends of the second story studding 2 receive a second top channel, and the ceiling joist may be supported thereupon. The ceiling joist is of similar construction to the floor joist, and suitable reenforcing bars 9 may be supported in the ceiling joist with ends bent downwardly to extend into the upper top channel 10, as shown best in Fig. 1. It should be here noted that the apertures 4c in the several joist members and 10c in the top channels may receive pins upon which the additional reenforcing bars 9 may rest prior to the pouring of concrete or the like.

If it is desired to support a sloping roof from the ceiling joist, rafters 11 may be provided. The rafters are identical in construction to the floor joists except that their widths are slightly less. As shown in Fig. 11, the rafters 11 are inserted in the ceiling joist in angular relation therewith, the securing lugs which would otherwise interfere being bent out of the way or broken off. The rafters are additionally held in their desired positions by the insertion of pins 3 through aligning apertures.

In the forming of interior partitions, the floor joist and floor slab are poured first, then base channels 12 are positioned along the floor so as to define the desired partitions. The channels 12 are similar to the channels 10 except that in place of the depending rib 10g, the base channel 12 is provided with a series of large openings 12a. When the partition studding has been positioned and the channels 12 filled with cement, said channels are tied through the openings with the floor slab. If desired, the partition base channels may be mounted before the floor slab is poured by suitably suspending it a desired distance above the floor reenforcing. If this is done, the channel may be filled with cement the same time the floor is poured.

75 If desired, in addition to the temporary secur-

ing arrangement afforded by the pins 3, the structural members may be tacked together by spot welding.

Though I have shown and described a particular construction, combination, and arrangement of parts and portions, I do not wish to be limited to this particular construction, combination, and arrangement, but desire to include in the scope of my invention the construction, combination, and arrangement substantially as set forth in the appended claims.

Having thus described my invention, what I claim as new and desire to secure by Letters Patent is:

1. In a building construction, combined frame and form elements formed of sheet material and bent to form the various structural members of a building construction, said structural members having a plurality of apertures therein, the apertures in the several structural members being so disposed that upon arrangement of the structural members in their various positions to form a building construction several apertures of adjacent structural members are in registry, tie members adapted to be inserted through such apertures to initially retain the structural members in position, said structural members having structural sections and defining channels adapted to receive plastic material, the apertures adapted to permit extrusion of a limited quantity of plastic material to provide irregular exterior surfaces facilitating the application of other plastic material, and anchor lugs extending into the channels formed by partially punching the material deleted to form the apertures. 35

2. In a building construction, combined frame and form elements formed of sheet material and bent to form the various structural members of a building construction, said structural members having a plurality of apertures therein, the apertures in the several structural members being so disposed that upon arrangement of the structural members in their various positions to form a building construction several apertures of adjacent structural members are in registry, tie members adapted to be inserted through such apertures to initially retain the structural members in position, meshwork extended between and across the structural members, and a backing for said meshwork connecting the structural members, said structural members defining channels, exposed to the meshwork, monolithic initially plastic material spread over the meshwork and into the channels, the apertures adapted to permit extrusion of limited quantities of plastic material to provide irregular exterior surfaces on the structural members, and a coating of plastic material spread over such exterior surfaces whereby the structural members are completely encased, and anchor lugs extending into the channel formed by partially punching the material deleted to form the apertures. 55

3. In a building wall construction, a series of alternating foraminous studding and channel members, the channel members being disposed horizontally across the upper ends of the studding therebelow and arranged to receive the lower ends of the studding thereabove, said studding likewise defining channel portions, the channel members and channel portions both provided with integral inwardly enlarging inwardly extending tying lugs, said channel members and channel portions serving as forms to receive plastic material whereby the lower ends of the stud- 75

ding are anchored in the channel members and serve as reinforcing for plastic material.

4. In a building wall construction, a series of alternating foraminous studding and channel members, the channel members being disposed horizontally across the upper ends of the studding therebelow and arranged to receive the lower ends of studding thereabove, said studding likewise defining channel portions, the channel members and channel portions both provided with integral inwardly enlarging inwardly extending tying lugs,

said channel members and channel portions serving as forms to receive plastic material whereby the lower ends of the studding are anchored in the channel members, means interlocking the channel members and studding, a meshwork connecting the studding, and a monolith plastic material applied in and around the studding and channel members and over the meshwork.

CLARENCE S. HARPER. 10
